UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S POLONAISE.

SPECIFICATION forming part of Design No. 15,367, dated August 26, 1884.

Application filed June 23, 1884. Term of patent 3½ years.

To all whom it may concern:

Be it known that I, CATHERINE O'HARA, of the city, county, and State of New York, have invented and produced a new and original 5 Design for a Pattern of a Lady's Polonaise, numbered 9,314; and I do hereby declare that the engraved prints accompanying this specification convey to any one accustomed to using paper patterns a clear understanding of how a 10 garment made up by the pattern will appear.

The design shows tight-fitting vest-fronts, displaying a closing all the way down; loose-fitting fronts that exhibit a gradual separation below the neck, display shirrings at the 15 neck and draping-plaits at the back edges, and assume a deeply-pointed outline at their lower

front corners; a close-fitting back that displays plaits at its front edges a little below the waist, and under-folded plaits at the lower ends of its middle three seams, and, descending below 20 the fronts, exhibits a square effect at its lower front corners; coat-sleeves and a standing collar.

What I claim as my invention, and desire to secure by Letters Patent, is—

The design for a lady's polonaise, as shown in the engraved prints accompanying this specification.

CATHERINE O'HARA.
